UNITED STATES PATENT OFFICE.

GOODWIN B. SMITH, OF NEW YORK, N. Y.

COIN-CONTROLLED VENDING MACHINE.

Application filed October 6, 1925. Serial No. 60,822.

The invention relates to a vending machine and relates more particularly to coin control vending machines of the non-selective type wherein the articles are contained in a plurality of compartments which are successively and progressively advanced to alignment or registry with a delivery opening, each progressive movement of the compartments being permitted and controlled by the insertion of a coin in a collection receptacle, thereby permitting the operating handle to be actuated.

An important object of the invention is to provide a coin control vending machine of the character described comprising a rotary drum having a plurality of radially disposed pockets adjacent its periphery, said pockets being in alignment with corresponding windows in the drum casing for the inspection of prospective purchasers, said drum being actuated by a centrally disposed handle to progressively bring said radial compartments into registry with a single dispensing door aperture in the drum casing.

A further object of the invention is to provide a vending machine of the character described so constituted as to cooperate with a coin control mechanism to permit the dispensing door to be opened only after the insertion of the proper coin.

A further object of the invention is to provide a machine of the character described which is incapable of actuation except upon the insertion of the proper coin together with means for automatically returning to the purchaser any undesired coin of any size capable of being inserted in the reception slot provided for the purpose.

A further and important object is to provide a vending machine constituting a rotary drum having radial article receiving compartments adapted to be moved progressively into registration with a normally closed door, the opening and closing of said door being controlled by suitable mechanism in turn controlled by the operating handle to move said door successively to open and closed position. It is contemplated in this regard that when the door is open the coin slot is obstructed to prevent the insertion of a coin therein, said obstruction being automatically removed when the door is closed. The invention further contemplates mechanism for effectively locking the drum against rotation in either direction both while said door is closed and while open as well as during the

operation of opening and closing said door. The insertion of the coin releases the locking mechanism temporarily to permit the drum to be advanced one step by the operating handle to bring a filled compartment into registration with the door opening, said door being automatically opened immediately thereafter by the continued movement of the operating handle, to permit access by the purchaser to the contents of the compartment.

A further object of the invention is to provide a machine of the character described in which suitable mechanism is provided to lock the drum and the coin control mechanism against further actuation after all of the contents of the radially disposed compartments have been sold, together with automatic means for visibly informing subsequent purchasers that the machine has been emptied of its contents.

A further object of the invention is to provide a machine of the character described which may be economically manufactured and assembled, with most of the working parts die-pressed, said parts being capable of being assembled rapidly and providing a machine which is extremely durable in its nature, as well as adequately protected against pillage by unscrupulous and unauthorized persons.

With such objects in view, as well as other advantages which may be incident to the use of the improvements, the invention consists in the parts and combinations thereof hereinafter set forth and claimed, with the understanding that the several necessary elements constituting the same may be varied in proportions and arrangement without departing from the nature and scope of the invention.

In order to make the invention more clearly understood there are shown in the accompanying drawings means for carrying the same into practical effect, without limiting the improvements, in their useful applications, to the particular construction which, for the purpose of explanation, have been made the subject of illustration. In the said drawings:

Fig. 1 is a front elevation of a preferred embodiment of the invention.

Fig. 2 is a plan view of the same.

Fig. 3 is a rear view of the front casing removed from the drum and displaying the mechanism for actuating the machine.

Fig. 4 is a detail front elevation, partially broken away and showing portions of the mechanism for automatically locking the machine when emptied, and displaying visible indicia to subsequent purchasers that such is the condition of the machine.

Fig. 5 is a front view of the machine with the casing removed and showing in elevation the rotatable drum having the radial pockets.

10 Fig. 6 is a central vertical sectional view partially in side elevation on line 6—6 of Fig. 1, and showing the machine partially assembled.

Fig. 7 is an enlarged detail view looking 15 from the front of the machine and showing the mechanism for opening and closing the door, said door being in closed position.

Fig. 8 is a similar view showing the position of the controlling and actuating elements 20 when the door is in open position.

Fig. 9 is a vertical sectional view on line 9—9 of Fig. 7, and showing a portion of the machine casing.

Fig. 10 is a detail fragmentary view similar to Fig. 8 and showing the position of the mechanism immediately prior to the door being closed.

Fig. 11 is a transverse horizontal sectional view on line 11—11 of Fig. 10.

30 Fig. 12 is a detail view on line 12—12 of Fig. 3.

Fig. 13 is a similar view on line 13—13 of Fig. 3.

Referring to the drawings, the machine 35 comprises a circular standard or frame 1 having legs 2 which may be suitably secured as at 3 to a table, wall or counter, said frame having a hub portion 4 and radiating legs or braces 5. The hub 4 is provided with a hollow horizontally projecting stud shaft 6 adapted to support externally a corresponding central hollow spindle or shaft 7 of a rotatable drum 8. The drum 8 is composed of a rear wall 9 centrally apertured to receive 40 the stud shaft 6, a front wall 10 and a plurality of radially disposed, preferably uniform pockets or compartments 11, the walls of the latter being secured in any desired manner to the circular walls of the drum. 45 As illustrated the walls of the radial compartments are shown as provided with integral lugs 12 adapted to be inserted in suitable slits in the circular walls of the drum 8 and thereafter clinched against said walls.

50 The drum element 8 further includes a gear wheel 13 rigidly secured by screws or bolts 14 to a triangular casting 15, the latter being secured by said screws or bolts to said drum and constituting a support for the central 55 hollow stud shaft 7 adapted to rotatably and externally engage the shaft 6 of the frame or standard 1. The triangular frame member 15 is further provided with a radially extending arm 16 having a locking projection 60 17 thereon for the purpose of locking the

drum when emptied in a manner which will be hereinafter described.

The drum 8 is rotatably supported on the standard 1 by means of the cooperating hollow shafts 6 and 7, and the drum is maintained in rotatable position on the spindle 6 by means of a front casing member 18 having a central shaft 19 adapted to be inserted within the hollow shaft 6 through a central aperture 20 in the gear 13. The casing 18 70 is of slightly greater diameter and circumference than the drum 8 to permit the desired rotation of the latter within said casing when the machine is assembled. The function of the plate, wall or casing 18 is to remain fixed 80 at the end of the drum during the rotation of the drum and to cover at all times the otherwise open sides of the said compartments 11 in the drum, said part 18 thus enclosing the drum more or less completely. A plurality 85 of lugs 21 of any desired number are suitably secured on the circumferential or annular part of the casing 18 which lugs are designed to cooperate with and engage behind corresponding lugs or wedges 22 on the circular standard or frame 1. The casing 18 is assembled by moving the lugs or ears 21 and 22 into transverse alignment and then engaging the same by a slight rotary movement 90 of the casing to the right to frictionally engage the lugs. The latter may be perforated as indicated for the reception of one or more padlocks 23 by means of which the machine is locked in its assembled position.

The front casing member 18 has integrally 100 formed therewith or secured thereto a coin control housing 24 having a coin reception slot 25 (Fig. 2). Suitable coin control mechanism is contained within the housing 24 which operates with the mechanism of the machine 105 to actuate the latter only when the proper coin has been inserted. The coin control mechanism is mounted on and actuated by the shaft 19 projecting at its forward end through a hub portion 25 and having an operating handle 27 keyed or otherwise rigidly secured to the forward end of said shaft. The particular construction of the coin control mechanism within the housing 24 forms 110 no part of the present invention and therefore will not be further described in detail. It is sufficient to state that this mechanism is operated by the manipulation of the handle 27 and that the coin must be first inserted in the slot 25 provided for the purpose. Any 115 improper coin of a denomination to permit the same to be inserted within the slot 25 fails to pass through the coin control elements and is returned to the customer through a circular recess 28 (Fig. 1) communicably connected 120 with the coin slot 25.

The casing 18 is further provided with an integrally formed sliding door housing 29 having an aperture 30 therein which is normally obstructed by the door when the latter 130

- is in closed position. The casing 18 is further provided with a plurality of window apertures 31 which may correspond in size, number and location with the radial compartments 11 of the drum 8 or may be proportionate in number thereto, so that the contents of said compartments are visible through the window apertures of the casing when the machine is assembled. The window apertures 31 have disposed therebetween radially extending ribs 32 preferably integrally cast with the casing 18. The ribs 32 are designed to have seated therebetween a plurality of glass windows corresponding in number and shape to the window apertures and which serve to protect the contents of the rotary drum and at the same time render said contents visible to prospective purchasers. The window glass sections are maintained in position within the central apertures by a circumferential flange forming a channel 33 formed on the casing 18 (Fig. 3) and are maintained in position at their inner ends by a circular ring or rings 34, the latter consisting of one or more sections and preferably having a covering of yieldable packing to minimize the danger of breaking the glass when being assembled or during the operation of the machine. The ring section or sections 34 is or are maintained in position against the radially innermost edges of the glass sections on the inner face of the casing 18 by means of a plurality of spring plates 35 yieldably pressed in engagement against the ring 34 by means of suitable screws or other fastening devices threaded into the projections 36, the latter being preferably integrally formed with the casing 18 (Fig. 12).
- 40 The sliding door or shutter is preferably constructed of a metallic rim or frame 37 having a plurality of lugs 38 adapted to maintain a glass section assembled in position within said door frame (Fig. 3). The door frame 37 which may correspond substantially in dimensions to one of the window sections, terminates in a depending portion 39 pivoted at 40 to a main door operating lever 41, the latter suitably pivotally supported as at 42 to the inner side of the casing 18. The depending portion 39 of the door frame is further provided adjacent its lower end with a pin or projection 43 having a limited lateral movement within a slot 44 formed in the upper end of the main door operating lever 41. The construction described permits limited swinging movement of the door frame 37 relative to its operating lever 41 to permit a certain amount of cushioning action of the door during the sliding movement thereof within its housing, thereby minimizing possible damage to the door structure. This described arrangement further permits the door to be swung radially from open to closed position and vice versa
- 45 from the pivot 42 of the main operating lever 41. The main door operating lever 41 is also preferably provided adjacent and below the depending portion 39, with a pin or projection 45 adapted to engage a depending bifurcated portion of the slide member 45^a controlling the coin slot. By this simple arrangement the slot is maintained closed to obstruct the passage therethrough of a coin when the door is open, the movement of said slide permitting the insertion of a coin when the door is swung to closed position.
- 50 The opening and closing of the door, the coin control, as well as the various mechanisms for periodically locking and releasing the rotary drum 8 at the proper intervals, is controlled by the central shaft 19 passing through and having suitable bearings in the coin control housing 24, said shaft being rotatably journaled at its inner end within the hollow central shaft 6 of the frame or standard 1. The several mechanisms described may be controlled and actuated by turning the operating knob or handle 27, fixed on the shaft 19, and the mechanism is such that the drum 8 may be actuated only when the door is closed and after a coin has been inserted in the slot 25. The knob 27 and shaft 19 are turned to the right to rotate the drum 8 one step to the left, and substantially simultaneously therewith the sliding door 37 is opened by the continued movement of the operating handle to permit access by the purchaser to the filled compartment which has been moved into registration with the door opening. The mechanism is further of such character that the drum 8 is securely locked in position at all times, whether the door is open or closed, except for the brief interval when it is being advanced one step by the operating handle, at which interval the door is in the act of opening. The mechanism is further of such character that the door is closed by a reverse movement of the operating handle or to the left, to render the coin slot free for the reception of a succeeding coin and to reset the controlling mechanism for a subsequent partial rotation of the drum to advance the succeeding filled compartment into registration with the door opening. The mechanism is further of such character that the door is alternately opened and closed rapidly with a minimum of effort on the part of the operator until the machine has been emptied of its contents.
- 55 The shaft 19 carries on its intermediate portion within the coin housing 24 a loosely mounted disk member 46, having a hub portion 47 on the inner side thereof, said hub portion being preferably cut-away as illustrated to provide diametrically opposed notches or recesses 48 and a pair of interposed projections 49. The disk member 46 is further provided adjacent the periphery thereof with a pair of diametrically opposed pins or

projections 50, 50^a to provide journals for corresponding rollers 51, 51^a. The shaft 19 is further provided with a transverse elongated rod 52 passing through a suitable aperture in said shaft, and the purpose of which rod is to actuate the mechanism for closing the door as will be hereinafter described.

Each of the rollers 50 and 51^a are designed to contact with the cam surface 53 on the main door operating lever 41 to move the latter and the door to open position on the rotation of the operating handle. Said rollers are also designed to contact with a corresponding cam surface 54 of a lever 55, pivotally mounted at 56 to the lever 41 and normally held by a spring 57 against a stop or lug 58 on the lever 41 to maintain the end of the locking lever 55 in engagement with a projection 59 preferably integrally cast with or formed on the casing 18, thereby normally preventing the door 37 from being opened.

The main door operating lever 41 has pivoted thereon as at 60 a rocking lever 61 having an upper projection 62 thereon, which projection when the door is closed and partially open is normally held by gravity and by the tension of a coil spring 63, pivoted to the opposite end 64 of said lever, in engagement with an inwardly projecting stationary shelf or bar 65 suitably secured at 65^a and 72 to the casing 18. The bar 65 is further provided on one edge thereof with a cut-away portion or recess 66 and an upstanding projection 67 for a purpose to be described. The projection 62 of the lever 61 is adapted to engage the cut-away portion 66 when the door is being opened thereby permitting said lever to drop, assisted by the spring 63 and this movement serves to engage a second lug or projection 68 thereof with the peripheral teeth 69 of the gear wheel 13, rigidly secured to the outer wall of the drum 8, to lock the drum. This engagement is preparatory to moving the drum the required distance to present a filled compartment thereof in registration with the door opening of the casing, on the continued movement of the operating handle. Prior to the locking engagement of the projection 68 with the gear wheel 13, the drum is locked in position by a lug or projection 70 on the lower end of one arm 71 of a bifurcated lever pivotally mounted at 72 to the casing 18. The projection 70 normally engages the peripheral teeth 69 of the gear wheel. When the projection 68 of the lever 61 drops down to lock the drum preparatory to moving the same as above described, said projection contacts with a second arm 73 of the bifurcated lever, thereby moving the latter and its projection 70 out of engagement with the gear wheel and against the tension of a coil spring 74 secured at one end to the arm 71 and secured at its other end as at 75 to a suitable projection on the casing 18. The action of the spring 74 is to normally

maintain arm 71 of the bifurcated lever against a suitable stop 76 on the casing and the projection 70 of said lever in locking engagement with the gear wheel 13 of the drum. A spacing block 77 may be provided between the arm 71 of the bifurcated lever and the casing 18 to insure the desired rocking movement of the lever into and out of locking engagement with the gear wheel teeth.

After the projection 68 has dropped into engagement with the gear teeth and projection 70 has by the same described movement become disengaged from said gear teeth, the continued rotation of the operating handle completes the movement of opening the door, by reason of the continued engagement of the roller 51 with the cam surface 53 of the pivoted main door lever 41, and this described movement results in the drum 8 being rotated the desired distance by reason of the engagement of projection 68 carried bodily by lever 41, with the peripheral teeth of the gear wheel 13.

The drum 8 is maintained against retrograde movement by means of a pawl 78 pivoted as at 79 to the casing 18 and having its tooth yieldingly maintained in engagement with the peripheral teeth of the gear wheel 13 by means of the coil spring 57, to permit rotation of the drum in one direction only, or in a clockwise direction as viewed in Fig. 3. The pawl 78 is limited in its normal tendency to be drawn toward the teeth of the gear wheel 13 by means of its tail 80 contacting with one of the projections 36 on the inner face of the casing 18. A fixed stop is thereby provided for the spring 57 for its cooperation with the door locking lever 55.

The door is closed as described by reverse rotation of the operating handle which for each successive closing movement, engages succeeding ends of the rod 52 with a projection 81 of a suitably weighted lever 82 pivoted at 83 to the casing 18. The continued reverse movement of the operating handle raises the lever 82 overcoming its weighted portion and bringing a second projection 84 thereof into engagement with the lower edge of a lever 85 pivoted at 86 to the casing and having an upturned portion 87 disposed in the path of the projection 68 of the rocking lever 61 when the door is in open position. The door 37 is normally locked in open position by the engagement of the shouldered end 88 of a locking lever 89 with a suitable projection 90 on the main lever 41. The lever 89 is also pivotally secured to the casing by means of the pivot 86 and is further provided with an upstanding tail portion 91 to which is secured one end of the spring 63. The latter therefore becomes in effect a floating spring. The locking lever 89 is further provided with a cut-away portion or recess 92 disposed in the path of the projection 84 of the weighted lever 82 so that the locking le-

ver 89 is also raised by said projection after the upward movement of lever 85 has lifted the projection 68 and lever 61 above the bar 65 preparatory to being returned by spring 63 into its normal position with projection 68 resting on said bar when the door is in closed position. It will be apparent that the door is closed by the tension of spring 63 after locking lever 89 has been lifted from engagement with projection 90 on main door operating lever 41.

In the operation of the vending machine and assuming the sliding door 37 to be in closed position, a coin is inserted in the slot 25 of the coin control housing 24 and the operating knob or handle 27 is turned to the right or in a clockwise direction as viewed in Fig. 1. The operating handle is keyed to the central shaft 19 and this rotary movement thereof is to the left or in a counter-clockwise direction as viewed in Fig. 3.

A cam member 92 is rigidly connected to or constructed integrally with the loosely mounted disk member 46 and serves to actuate the coin control mechanism to carry the coin from the slot into its collection receptacle when the shaft 19 is rotated. The shaft 19 reaches its limit of free movement by the engagement of the rod 52 with the upper wall of the recess 48 and lower wall of the opposite recess, and thereafter the disk member 46 rotates coincident with the shaft. This movement continues until the roller 51 engages the curved cam surface 54 of the lever 55 pivoted at 56 to the main operating lever 41 of the sliding door. The roller 51 thereafter travels along the cam surface 54 thereby swinging the lever 55 upwardly on its pivot to disengage its extremity from the locking projection 59 on the casing. This releases the normally locked lever 41 and permits the sliding door 37 on the upper end thereof to be opened by further rotation of the shaft 19. The continued movement of the handle brings the roller 51 into engagement with the curved cam surface 53 of the main door operating lever 41 and swings the latter outwardly on its pivot 42 against the tension of the coil spring 63 and to the right as viewed in Fig. 3. As the main pivoted lever 41 moves to the right against the tension of the spring 63, this spring tension also tends to swing downwardly the free end of the pivoted lever 61, but the latter is prevented from dropping downwardly by the engagement of the projection 62 with the horizontally disposed bar 65. The latter is cut away as described at substantially its middle portion 66 to provide clearance for the lug 62 after the latter has traveled to this point on the bar 65. Thereafter during the continued rotary movement of the operating handle the lever 61 is permitted to drop downwardly when the lug 62 reaches the recess 66 and the lower portion 68 of the free end of said lever engages the end

73 of the bifurcated lever 71 to move the latter out of locking engagement with the gear wheel 13 and simultaneously engage the lug 68 with the teeth of said gear wheel.

The drum 8 carrying the articles to be dispensed in its several radial compartments, is now free to be rotated by lug 68 on the continued movement of the operating handle, to move a filled compartment into registry with the door opening covered by sliding door 37. It will be noted that the downward movement of the lever 61 to move the lever arm 71 out of locking engagement with the gear 13 of the rotary drum occurs when the sliding door 37 has been moved only partially open and, while the drum is free to be rotated by a continued movement of the operating handle at the time it is unlocked, an empty compartment is still in registry with the partially open door. It might be further stated that in this position of the mechanism the coin has been carried around within the coin control housing out of alignment with the slot 25 in which it was inserted. It will be further noted that in the described position of the elements, the door is prevented from being closed by the pull of the spring 27, by means of a depending projection 98 of the stationary bar 65 now disclosed in the path of the lug 62 of the lever 61 when the lower projection 68 of the latter is resting against the arm 73 of the lever 71.

The continued rotation of the operating handle carries the roller 51 further along the curved cam surfaces 54 and 53 of the levers 55 and 41 thereby projecting the main operating lever 41 further to the right. This produces a corresponding bodily movement in the same direction of the lever 65 carried by the lever 41. As the projection 68 of the lever 65 is now engaged between the peripheral teeth of the gear 13, this described movement to the right of the lever 41 partially rotates the drum 8 a sufficient distance to bring a filled compartment thereof into registry with the sliding door 37 which by this same movement is now completely open for the customer to obtain access to the contents of said filled compartment. As above described the door is moved to open position by the engagement of the roller 51 with the cam surface 53 of the pivoted lever 41.

At this time when the roller 51 clears the cam surface 53 of the lever 41 said lever and the door carried thereby are locked in open position by the shouldered end 88 of the lever 89 dropping into engagement with the projection 90 on the lever 41 and maintained in locking position by the tension of the floating coil spring 63. The spring 63 exerts tension on the arm 91 which is preferably an integral upstanding portion of the pivoted lever 89.

At substantially the time when the door has been moved completely open against the tension of the spring 63 and locked as de-

scribed in open position, the roller 51 clears the curved cam surface 54 of the lever 55 and the latter is immediately pulled downwardly by the coil spring 57 to move one of the notches 99 of lever 55 into locking engagement with the projection 59 on the casing 18. It will be further observed that in the described open position of the door, the projection 68 of the lever 65 is still in engagement with the teeth of the gear wheel 13 of the drum and the latter can therefore be rotated a succeeding step only after the door has been closed. The engagement of the notch 99 of the lever 55 with the projection 59 locks the sliding door against further movement in the direction of the rotary drum 8 while the door is open, and therefore it is only possible to remove the contents of the compartment which has been presented in registry with the door aperture during the operation of moving said door to open position.

In order to further insure the rotation of the drum carrier in one direction only (in a clockwise direction as viewed in Fig. 1), the pawl 78, pivoted at 50 to the casing, is normally pressed into engagement with the peripheral teeth of the gear 13 by means of the coil spring 57 secured to said pawl. The tail 80 of the pawl is normally engaged by said spring with the stop 36 on the casing to limit the movement of the pawl in one direction and to further insure a working engagement of the spring 57 with the pivoted lever 55. It will therefore be apparent that the pawl 78 permits the carrier drum to be rotated in one direction only and the engagement of its tooth with the gear 13 prevents reverse movement of the drum, which is of special utility when the machine has become partially emptied of its contents while in use, resulting in the drum having a tendency for retrograde movement due to the weight of the articles carried thereby.

As heretofore stated in order to obtain access to the next succeeding compartment of the drum carrier it is first necessary to close the door 37, which action uncovers the slot 25 of the coin control housing and places the coin reception mechanism in position to receive another coin. The door is closed by the same or a succeeding customer by reverse movement of the operating handle 27 or in a counter-clockwise direction as viewed in Fig. 1 and a clockwise direction as viewed in Fig. 3. The operation of the mechanism to permit the door to be closed by said reverse movement of the knob 27 is as follows:

Referring to Figs. 3, 7 and 8, free movement of the shaft 19 is permitted until the opposite end of the rod 52 engages a projection 49 of the loosely mounted disk member 46. The subsequent rotation of the disk member in a reverse direction serves through connected spring actuated mechanism rotat-

ing therewith on shaft 10 to reset the coin control mechanism to receive a subsequent coin. At the time this reverse rotation is commenced one end of the rod 52 engages the projecting lug 81 of the rocking lever 82 pivoted at 83 to the casing. The continued rotation of the operating handle and shaft 19 in reverse direction raises the projection 84 of the rocking lever 82 thereby successively raising the pivoted levers 85 and 89 respectively from their position at rest against the fixed stop 85^a on the casing. The rearmost lever 89 as viewed in Fig. 3, is provided with a cut-away portion or recess 92 adjacent the projection 84 of the lever 82, the presence of which recess permits the outer lever 85 to be first raised independently of lever 89 a distance corresponding to the depth of said recess. This independent movement of lever 85 engages the upturned end 87 thereof with the lower lug 68 of the pivoted lever 61 to move the latter upwardly against the tension of floating spring 63. This movement permits tension spring 74 to again move locking projection 70 on arm 71 of lever pivoted at 72 into engagement with the teeth 69 of gear 13 to once more lock the drum 8 against rotation in either direction. The stop 76 serves as an auxiliary limit to inward movement of the arm 71. At the time the drum is again locked by the projection 70 engaging the gear teeth, projection 84 of lever 82 engages the rear wall of recess 92 and thereafter pivoted levers 85 and 89 are moved upward simultaneously. The further function of lever 85 is to lift rocking lever 61 until projection 62 thereof passes through the cut-away portion 66 of stationary bar 65 and is lifted above and clear of a downturned projection 66^a (Figs. 3, 7 and 8) on said bar 65, and said projection 62 is therefore in position to be moved to the left as viewed in Fig. 3 to again support lever 61 in raised position by the engagement of projection 62 thereof with the bar 65. This desired and described re-engagement of projection 62 with bar 65 is effected by the door being closed immediately by spring 63 upon the described lifting of lever 61. This movement of the door to closed position is permitted by lever 89 being lifted by projection 84 on lever 82 after said projection has reached the inner wall of the recess 92 on said lever. The upward movement of lever 89 releases the notched or cut-away portion 88 thereof from engagement with projection 90 on the main door operating lever 41, thereby permitting the latter and the door carried thereby to be rapidly moved to the right (Fig. 7) to closed position by the tension of coil spring 63. All of the elements of the mechanism are now in position to permit the door to be again opened and rotary drum 8 rotated another step, upon the insertion of a coin and through the rotation of the operating handle 27 to

the right as viewed in Fig. 1 and to the left as viewed in Fig. 7, upon which occasion the various elements cooperate and perform their respective functions as has been hereinabove described.

The function of the upstanding projection 67 on bar 65 is to positively engage lug 62 at the time the latter reaches the cut-away portion 66 of the bar 65 when the door is being opened and to insure the lever 61 dropping downwardly assisted by spring 63 to engage the rocking arm 73 to unlock the drum by projection 70 and lock said drum by means of projection 68. Were it not for the provision of the upstanding projection 67, it might be possible through a quick and sudden movement of the operating handle, to cause the projection 68 to travel past the cut-away portion 66, and the consequent failure of the lever 61 to drop down might cause the lower projection 68 of the lever 61 to skip or fail to engage the proper tooth of the gear wheel 13, thereby resulting in the failure of projection 68 to serve its further function of releasing gear wheel 13 through its engagement with arm 73 of lever 71 with probable jamming of the mechanism.

When all of the radial compartments 11 of the drum 8 have been emptied of their contents, the machine is designed to become automatically locked with the door in open position. When the door is in open position the coin slot is obstructed by the sliding shutter 45 controlled by the pin 45 on the lever 41, the position of said slide to obstruct or expose the coin slot depending on the position of said lever. The drum filled with merchandise has been inserted in the casing in a predetermined position so that a definite compartment is first relieved of its contents, and the other compartments are subsequently emptied progressively and in succession. When the drum has been rotated to present the last compartment containing merchandise to be vended into registry with the door aperture, the locking projection 17 on the radially projection arm 16 mounted rigidly with the gear wheel 13 and drum, comes in contact with a corresponding projection 93 rigidly secured to the pivoted lever 85. This engagement prevents the usual reverse movement of the operating handle to lift levers 85 and 89 as heretofore described in order to close the door. Said lever 85 cannot be rocked upwardly by lever 82 because of the contact of stop 93 thereof with projection 17 carried by the drum. The drum cannot be rotated in the opposite direction, or forward, to release engagement of projections 17 and 93 by reason of the described engagement of locking projection 68 of lever 61 with the peripheral teeth of the gear wheel 13.

In this position of the machine, and as a further notice to the public that all of the contents have been sold, the last remaining

filled receptacle is preferably provided with a flap 94 (Fig. 4) preferably suitably hinged to the drum periphery and which is normally maintained pressed inwardly in unexposed position by the contact against it of the merchandise to be vended. When this merchandise is removed the hinged flap 94 drops down by gravity to the position shown in Fig. 4 to display the word "Empty" or the like through the door aperture 30 to indicate to subsequent purchasers that the contents of the machine have been sold out.

It is now necessary to restock the machine, which operation is effected by unlocking the padlock 23 and removing the casing from the drum thereby exposing all of the radial compartments to view. After the compartments have been filled with the merchandise to be sold the casing 18 is replaced but with the last compartment to be again emptied immediately to the right of the door opening as viewed in Figs. 1 and 4, which act of positioning places the cooperating lugs or projections 17 and 93 in reverse position to permit a complete rotation of 360 degrees of the drum before said projections again come into locking engagement (Fig. 4). It will be apparent that the replenishment of the drum with merchandise serves to once more swing back to unexposed position the flap 94 bearing the word "Empty" or the like.

In order to insure the proper positioning of the cooperating lugs 17 and 93 to permit a rotation of 360 degrees of the drum, the casing 18 may be positioned over the filled drum with the aid of any suitable pointed implement which is inserted through an aperture 95 in the circular frame 1 (Fig. 2), and through a corresponding aperture 96 in the drum 8 which has been positioned upon the central spindle 6 carried by the frame 1. The casing 18 is next positioned or telescoped over the drum with a notch 97 on its periphery coinciding with the aligned apertures 95 and 96, said notch 97 permitting the drum to be slipped past the pointed implement which maintains apertures 95 and 96 in alignment. When the apertures 95 and 96 and notch 97 are aligned as described, the peripheral ears 21 on drum 18 occupy their proper position to the left or and in a plane within the circumferential plane occupied by the cooperating ears 22 on the frame 1. The positioning pin or implement is removed and a slight rotary movement of the casing to the right serves to securely engage the peripheral cooperating lugs 21 and 22 as illustrated in Figs. 1 and 2, and the padlock 23 is attached through one pair of the cooperating lugs to securely lock the machine in assembled relation.

The present application is designed to cover more particularly the improved and simplified mechanism for actuating a normally closed and locked vending machine of the

non-selective drum type, after the coin controlled mechanism is released by the insertion of the proper coin. Any desired and suitable form of coin controlled mechanism 5 may be used in conjunction with the present improvements to permit the main operating shaft to be rotated by its operating handle. For example, a coin control may be utilized such as is fully described in my co-pending 10 application Serial No. 464,770, filed April 27, 1921 for coin controlled device. An examination of the coin controlled mechanism described in my said co-pending application 15 will aid in a complete understanding of the present machine and said other application is hereby made a part hereof so far as it is necessary to the understanding and operation of the invention herein claimed.

What I claim is:—

- 20 1. A vending machine comprising in combination: a frame, a drum having radially disposed compartments rotatably supported thereby, a casing, having a door aperture and a sliding door normally closing the same, adapted to be positioned on said frame to house said drum, means carried by said casing for progressively rotating said drum and actuating said door to successively align the radial compartments of said drum with said door aperture, cooperating means carried by said casing and said drum to prevent the continued movement of the latter after a complete revolution, said cooperating means further preventing the door from being closed 25 after the complete revolution of said drum, and means carried by said drum automatically operative after said complete revolution to visually indicate that said drum is locked against rotation.
- 30 2. In a coin controlled vending machine the combination of: a frame, a drum having a plurality of radial compartments open at their sides adapted to be rotatably mounted on a horizontal axis on said frame, a casing adapted to be secured to said frame to house said drum and having an operating shaft journalled therein, means carried by said casing and controlled by said shaft for rotating said drum, means carried by said casing for normally locking said drum against rotation, said drum rotating means being operative to disengage said drum locking means to permit said drum to be rotated, and auxiliary means controlled by said drum rotating 35 means for locking said drum against rotation after said drum locking means have been disengaged.
- 40 3. A coin controlled vending machine comprising in combination: a frame, a drum having radially disposed compartments adapted to be rotatably mounted on said frame, a casing, having coin controlled mechanism and a door aperture, adapted to be secured to said frame to house said drum, said door aperture being adapted to register with the radial compartments of said drum when said casing is assembled, means carried by said casing normally locking said drum against rotation, a shaft having an operating handle journalled in said casing, a door operating lever having a sliding door pivotally mounted on said casing, said door normally closing said door aperture, means mounted on said casing normally maintaining said door in closed position, means carried by said door operating lever and cooperating with said casing to normally prevent said lever and said door from being moved to open position, means carried by said shaft adapted to disengage said door locking means and engage said door operating lever to move the door to open position, means pivotally mounted on said casing cooperating with said lever to maintain the door in open position, means carried by said door operating lever for temporarily disengaging said drum locking means when said door is moved to open position, said lever carried means being further operative to lock said drum against rotation after the drum has been rotated by the movement of said operating lever and said door to open position, and means carried by said casing and cooperating with said drum to maintain the latter against retrograde movement when said drum is being rotated by said lever carried means.
- 45 4. A coin controlled vending machine comprising in combination: a frame, a drum having radially disposed compartments adapted to be rotatably mounted on said frame, a casing having coin controlled mechanism and a door aperture adapted to be secured to said frame to house said drum, said door aperture being adapted to register with the radial compartments of said drum when said casing is assembled, means carried by said casing normally locking said drum against rotation, a shaft having an operating handle journalled in said casing, a door operating lever having a sliding door pivotally mounted on said casing, said door normally closing said door aperture, means mounted on said casing normally maintaining said door in closed position, means carried by said door operating lever and cooperating with said casing to normally prevent said lever and said door from being moved to open position, means carried by said shaft adapted to disengage said door locking means and engage said door operating lever to move the door to open position, means pivotally mounted on said casing cooperating with said lever to maintain the door in open position, means carried by said door operating lever for temporarily disengaging said drum locking means when said door is moved to open position, said lever carried means further operating to engage said

drum and rotate the same after said drum locking means have been disengaged, said lever carried means being further operative to lock said drum against rotation after the 5 drum has been rotated by the movement of said operating lever and said door to open position, means carried by said casing and co-operating with said drum to maintain the latter against retrograde movement when 10 said drum is being rotated by said lever carried means, said door operating lever engaging means carried by said shaft being adapted to disengage said pivotally mounted door holding means to permit said door to be 15 moved to closed position, and means pivotally mounted on said casing adapted to be engaged by said door lever operating means on said shaft to engage said lever carried means to permit said drum locking means to reengage 20 said drum and lock the same against rotation when said door is moved to closed position.

5. In a coin controlled vending machine the combination of: a frame, a drum having a plurality of radial compartments open at their sides, adapted to be rotatably mounted on a horizontal axis on said frame, a casing adapted to be secured to said frame to cover the open sides of said compartments, said casing 25 having an operating shaft journaled therein, means carried by said casing and controlled by said shaft for rotating said drum, and means carried by said casing for normally locking said drum against rotation, said drum 35 rotating means being operative to disengage said drum locking means to permit said drum to be rotated.

6. In a coin controlled vending machine the combination of a rotary drum, a casing adapted to house said drum, a door mounted on said casing, an operating shaft journaled in said casing, and means mounted on said casing and actuated by said shaft for rotating said drum and opening and closing said door in timed relation to the rotation of said drum. 40

7. A vending machine comprising a rotatable drum having radial compartments open at their sides, a casing adapted to house said drum and having a door aperture registering with said radial compartments, a door carried by said casing and normally closing said aperture, a shaft having an operating handle journaled in said casing, means carried by said casing and controlled by said shaft for 50 opening and closing said door, and means carried by said casing and controlled by said door actuating means for progressively rotating said drum in timed relation to the opening and closing of said door.

60 8. In a coin controlled vending machine the combination of a rotatable drum having radially disposed compartments open at their sides, a casing having a door aperture adapted to house said drum and close the open sides of said compartments, said door aperture being

adapted to register with one of said radial compartments of said drum when said casing is assembled, means carried by said casing normally locking said drum against rotation, a shaft having an operating handle journaled 70 in said casing, a door operating lever having a sliding door pivotally mounted on said casing, said door normally closing said door aperture, means carried by said door operating lever and cooperating with said casing to 75 normally prevent said lever and said door from being moved to open position, means carried by said shaft adapted to disengage said door locking means and engage said door operating lever to move the door to open position, means pivotally mounted on said casing cooperating with said lever to maintain the door in open position, and means carried by said door operating lever for temporarily 80 disengaging said drum locking means when 85 said door is moved to open position, said lever carried means further operating to engage said drum and rotate the same after said drum locking means have been disengaged, 90 said lever carried means being further operative to lock said drum against rotation after the drum has been rotated by the movement of said operating lever and said door to open position.

9. In a coin controlled vending machine 95 the combination of: a frame, a drum having radially disposed compartments adapted to be rotatably mounted on a horizontal axis on said frame, a casing having a door aperture adapted to be secured to said frame to house 100 said drum, said door aperture being adapted to register with one of said radial compartments of said drum when said casing is assembled, means carried by said casing normally locking said drum against rotation, 105 a shaft having an operating handle journaled in said casing, a door operating lever having a sliding door pivotally mounted on said casing, said door normally closing said door aperture, means mounted on said casing 110 normally maintaining said door in closed position, means carried by said door operating lever and cooperating with said casing to normally prevent said lever and said door from being moved to open position, means carried by said shaft adapted to disengage 115 said door locking means and engage said door operating lever to move the door to open position, means pivotally mounted on said casing cooperating with said lever to maintain the door in open position, means carried by said door operating lever for temporarily 120 disengaging said drum locking means when said door is moved to open position, said lever carried means further operating to engage said drum and rotate the same after said drum locking means have been disengaged, 125 said lever carried means being still further operative to lock said drum against rotation after the drum has 130

- been rotated by the movement of said operating lever and said door to open position, said door operating lever engaging means carried by said shaft being adapted to disengage said pivotally mounted door holding means to permit said door to be moved to closed position, and means pivotally mounted on said casing adapted to be engaged by said door lever operating means on said shaft
- 5 10. In a coin-controlled vending machine, the combination of a rotary drum having compartments arranged in a series around its center and open at their front ends, a fixed casing wall covering said front ends of the compartments and having a door aperture, a door mounted on and movable parallel with said wall, means for turning the drum to bring a compartment in delivery position behind said door, said means including a power shaft extending through said wall and means whereby said shaft can turn the drum, means actuated by said shaft for moving the door to open position, means for holding the drum from turning, and means actuated by said shaft for releasing the drum
- 15 20 25 30 35 40 45
- for a limited time prior to the complete opening of the door.
11. In a coin-controlled vending machine, the combination of a rotary drum having compartments arranged in a series around its center and open at their front ends, a fixed casing wall covering said front ends of the compartments and having a door aperture, a door and lever pivotally mounted on and movable parallel with said wall, means for turning the drum to bring a compartment in delivery position behind said door, said means including a power shaft extending through said wall and means whereby said shaft can turn the drum, means actuated by said shaft for swinging the door to open position,

sition, means for holding the drum from turning, and means actuated by said shaft for releasing the drum for a limited time prior to the complete opening of the door.

12. In a coin-controlled vending machine, the combination of a rotary drum having compartments arranged in a series around its center and open at their front ends and having a central space at the inner ends of said compartments and a gear wheel fixed to said drum, a fixed casing wall covering said front ends of the compartments and having a door aperture, a door mounted on and movable parallel with said wall, means for turning the drum to bring a compartment in delivery position behind said door, said means including a power shaft extending through said wall and means engageable with said gear wheel whereby said shaft can turn the drum, means actuated by said shaft for moving the door to open position, means for holding the drum from turning, said power shaft and means operated thereby being mounted on the casing wall and arranged in said central space.

13. A vending machine comprising a rotatable drum arranged in substantially vertical planes and with a substantially horizontal axis and having radial compartments open at their front sides, a casing adapted to house said drum and having a door aperture registering with said radial compartments, a door carried by said casing and normally closing said aperture, a shaft having an operating handle journaled in said casing, means carried by said casing and controlled by said shaft for opening and closing said door, and means carried by said casing and controlled by said door actuating means for progressively rotating said drum in timed relation to the opening and closing of said door.

In testimony whereof I affix my signature.

GOODWIN B. SMITH.
